(57) **CLAIM**

The ornamental design for a fire tool ladder collar as shown and described.

DESCRIPTION

FIG. 1 is a perspective view of a fire tool ladder collar showing my new design;

FIG. 2 is a left side elevation view thereof;

FIG. 3 is a right side elevation view thereof;

FIG. 4 is a front elevation view thereof;

FIG. 5 is a back elevation view thereof;

FIG. 6 is a top plan elevation view thereof;

FIG. 7 is a bottom plan elevation view thereof;

FIG. 8 is a perspective view of a fire tool ladder collar illustrated in a closed configuration coupled to a fireman's ladder thereof; and,

FIG. 9 is an exploded view of a fire tool ladder collar illustrated in an open configuration coupled to a fireman's ladder thereof.

The broken lines depict unclaimed environmental subject matter and form no part of the claim.
